(**) Term: **14 Years**

(57) **CLAIM**

(21) Appl. No.: **29/178,756**

The ornamental design for an automobile, as shown and described.

(22) Filed: **Mar. 31, 2003**

DESCRIPTION

(30) **Foreign Application Priority Data**

Oct. 1, 2002 (JP) 2002-026967

FIG. 1 is a front view of our new design for an automobile;

(51) LOC (7) Cl. **12-08**

FIG. 2 is a rear view thereof;

(52) U.S. Cl. **D12/91**

FIG. 3 is a top view thereof;

(58) Field of Search D12/90-92, 86;
296/185, 183

FIG. 4 is a bottom view thereof;

(56) **References Cited**

FIG. 5 is a right view thereof;

U.S. PATENT DOCUMENTS

FIG. 6 is a left view thereof;

D401,185 S * 11/1998 McGovern D12/91
D411,815 S * 7/1999 Yamamoto et al. D12/91
D422,533 S * 4/2000 Uematsu et al. D12/91
D424,980 S * 5/2000 Hunter et al. D12/91
D460,022 S * 7/2002 Hsu et al. D12/91
D466,053 S * 11/2002 O'Connell et al. D12/91

FIG. 7 is a front perspective view thereof;

FOREIGN PATENT DOCUMENTS

FIG. 8 is a rear perspective view thereof;

JP HEI2-19506 S 7/1992

FIG. 9 is a front perspective of an automobile showing a second embodiment of our new design illustrating transport and translucent parts; and,

FIG. 10 is a rear perspective view of FIG. 9.

The broken line portions of the drawings are for illustrative purposes only and form no part of the claimed invention.
